CLAIM

The ornamental design for an exercise band, as shown and described.

DESCRIPTION

FIG. 1 is a perspective view of an exercise band showing our new design;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

The broken line showing of portions of the exercise band depicts environment and forms no part of the claim.

1 Claim, 5 Drawing Sheets
